US00D662099S

(12) **United States Design Patent**
Cullen et al.

(10) **Patent No.:** **US D662,099 S**
(45) **Date of Patent:** **** Jun. 19, 2012**

(54) **PORTABLE HOUSING AND KEYPAD**

(75) Inventors: **Benjamin James Cullen**, London (GB);
Edward Anthony Hackett, Tolworth
Surbiton (GB); **Greg Evans**,
Merrickville (CA)

(73) Assignee: **Psion Teklogix Inc.**, Ontario (CA)

(**) Term: **14 Years**

(21) Appl. No.: **29/377,583**

(22) Filed: **Oct. 22, 2010**

(30) **Foreign Application Priority Data**

Apr. 23, 2010 (CA) 135144

(51) **LOC (9) CL.** **14-02**

(57) **CLAIM**

We claim the ornamental design for a portable housing and keypad, as shown and described.

DESCRIPTION

FIG. 1 is a front elevational view of a portable housing and keypad;

FIG. 2 is a side elevational view thereof; and,

FIG. 3 is an opposite side elevational view.

The broken line portions are not claimed. The dash-dot lines indicate the boundaries of unclaimed broken line portions.
